(57) **CLAIM**

The ornamental design for a display screen or portion thereof with animated graphical user interface, as shown and described.

DESCRIPTION

FIG. 1 is a front view of a display screen or portion thereof with animated graphical user interface showing a first image in the sequence showing my new design, according to a first embodiment;

FIG. 2 is a second image thereof;

FIG. 3 is a front view of a display screen or portion thereof with animated graphical user interface showing a first image in the sequence showing my new design, according to a second embodiment;

FIG. 4 is a second image thereof;

FIG. 5 is a top view of the portable terminal;

FIG. 6 is the bottom view thereof;

FIG. 7 is the rear view thereof;

FIG. 8 is the left side view thereof; and,

FIG. 9 is the right side view thereof.

The appearance of the animated design sequentially transitions between the images shown in FIGS. 1-2 and 3-4, respectively. The process or period in which one image transitions to another forms no part of the claimed design. The broken line showing of a display screen is included for the purpose of illustrating portions of the article and forms no part of the claimed design; the broken line showing of a portable terminal is included for the purpose of illustrating environmental structure and forms no part of the claimed design.
